IRRADIATION SYNTHESIS OF SULFONYL VINYLAMINES

Blaine Chase McKusick and John Carl Sauer, Wilmington, Del., assignors to E. I. du Pont de Nemours and Company, Wilmington, Del., a corporation of Delaware

No Drawing. Filed Mar. 4, 1957, Ser. No. 643,490
13 Claims. (Cl. 204—154)

This invention relates to, and has as its principal object provision of, a new process for synthesizing certain ethylenically-unsaturated amines having a sulfone group.

Ethylenically-unsaturated compounds are an important class of organic materials that have found widespread use due to the reactivity of the carbon-to-carbon double bond. Thus, the vinyl compounds are of considerable commercial importance for the preparation of polymeric materials by self-addition to the double bond. A further type of valuable reaction possible to such compounds is the addition of other elements or compounds to the ethylenic double bond.

The present invention provides a process in which certain ethylenically-unsaturated sulfonamides are molecularly rearranged to yield sulfonylvinylimines. More specifically, N-hydrocarbo-2-hydrocarbosulfonylvinylamines are obtained by rearrangement of the corresponding N-vinylsulfonamides under the influence of substantial amounts of ionizing radiation according to the equation:

wherein R and R' are hydrocarbon radicals of generally not more than 12 carbons each and are preferably alkyl or aryl. The compounds obtained can be referred to as 1-hydrocarboamino-2-hydrocarbosulfonyl ethylenes as well as N-hydrocarbo-2-hydrocarbosulfonylvinylamines.

In the general formula of the products obtained,

R and R' are hydrocarbon radicals free from open chain unsaturation with not more than 12 carbons each, i.e., 1-12 carbon atoms, and may be either the same or different. The preferred compounds have alkyl or aryl hydrocarbon groups of generally not more than 7 carbons. Examples of the hydrocarbon radicals that are embraced include methyl, ethyl, butyl, hexyl, cyclohexyl, phenyl, tolyl, naphthyl, and diphenyl for R and R'.

Examples of compounds included in the N-hydrocarbo-2-hydrocarbosulfonylvinylamines of the invention are, in addition to those described elsewhere in this specification, N-phenyl-2-phenylsulfonylvinylamine, N-n-butyl-2-n-butylsulfonylvinylamine, N-cyclohexyl-2-o-tolylsulfonylvinylamine, N-ethyl-2-p-tert-butylphenylsulfonylvinylamine, and N-n-hexyl-2-phenylsulfonylvinylamine.

The N-vinylsulfonamides utilized as starting materials in the invention are readily available from the reaction of acetylene with sulfonamides, according to U.S. 2,317,804, 2,324,896, and Cairns and Sauer, J. Org. Chem. 20, 627 (1955). Suitable N-vinylsulfonamides that can be employed include N-ethyl-N-vinyl-p-tert.butylphenylsulfonamide, N-n-butyl-N-vinyl-n-butanesulfonamide, N-cyclohexyl-N-vinyl-o-toluenesulfonamide, and N-n-hexyl-N-vinylbenzenesulfonamide.

The "ionizing radiation" utilized now to bring about the rearrangement of the N-vinylsulfonamides includes both radiation in the form sometimes regarded as particle radiation and radiation in the form sometimes regarded as ionizing electromagnetic radiation.

By "particle radiation" is meant an emission of accelerated electrons or nuclear particles such as protons, neutrons, alpha-particles, deuterons, beta-particles, or the

like, so that the said particle impinges upon the sulfonamide. The charged particles can be accelerated by means of a suitable voltage gradient, using such devices as a cathode ray tube, resonant cavity accelerator, a Van de Graaff accelerator, a betatron, a synchrotron, a cyclotron, or the like, as is well known to those skilled in the art. Neutron radiation can be produced by suitable nuclear reactions, e.g., bombardment of selected light metal (beryllium) targets with deuterons or alpha-particles. In addition, particle radiation suitable for carrying out the process of the invention can be obtained from an atomic pile, or from radioactive isotopes or from other natural or artificial radioactive materials.

By "ionizing electromagnetic radiation" is meant radiation of the type produced when a metal target (e.g., gold or tungsten) is bombarded by electrons possessing appropriate energy. Such radiation is conventionally termed X-ray. In addition to X-rays produced as indicated above, ionizing electromagnetic radiation suitable for carrying out the process of the invention can be obtained from a nuclear reactor ("pile") or from natural or artificial radioactive material. In these latter cases the radiation is conventionally termed gamma rays.

It is recognized that the energy characteristics of one form of ionizing radiation can be expressed in terms which are appropriate for another form. Thus, one may express the energy of either the particles of radiation commonly considered as particle radiation or of the photons of radiation commonly considered as wave or electromagnetic radiation in electron volts (e.v.) or million electron volts (mev.). In the irradiation process of this invention, radiation consisting of particles or photons having an energy of 0.1 mev. and over is preferred. With radiation of this type, rearrangement of the vinylsulfonamides can be obtained from the crystalline materials with a minimum length of exposure to the radiation, permitting maximum efficiency in utilization of the radiation. Particles or photons with an energy of 0.5-4 mev. are the most useful from a practical standpoint.

A minimum exposure of at least 0.1 watt-sec./cm.² of surface is necessary since lower degrees of exposure do not give effective rearrangement. The rate of rearrangement per unit of absorbed energy usually increases with decreasing beam intensity. Exposures as high as 1000 to 10,000 watt-sec./cm.² may be employed. The exposure may be carried out in one slow pass or in several faster ones and may be conducted at any convenient rate of energy input.

The rearrangement of this invention is carried out preferably in the solid phase although the liquid phase can be used. A temperature of about 0-50° C. is usable with room temperature preferred. Pressures are not important and ambient atmospheric pressure is generally employed.

The vinylamines of the invention are isolated by taking advantage of the difference in physical and chemical properties possessed by the new compounds. Fractional crystallization is perhaps the preferred method of separation since the sulfonylamines are generally much higher melting than the initial vinylsulfonamides. Fractional distillation is sometimes a useful method of separation since the sulfonylamines also generally have higher boiling points than the corresponding vinylsulfonamides.

The product sulfonylamines differ considerably from the starting vinylsulfonamides. In general, they have much higher melting points, higher boiling points, lesser solubility in organic solvents, and ultraviolet absorption maxima at longer wave lengths than the corresponding vinylsulfonamides.

The new compounds differ also in chemical properties from the vinylsulfonamides. Mild acid hydrolysis, for example, converts them to sulfonylacetraldehydes.

The following examples, in which parts are by weight, further illustrate specific embodiments of this invention. In the absorption data given, λ is the wave length, ϵ the molecular extinction coefficient, and k the specific extinction coefficient as defined by Harrison, Lord and Loobourow, "Practical Spectroscopy," Prentice-Hall, N.Y. (1948), pages 363-365. EtOH represents ethanol.

EXAMPLE 1

N-methyl-2-phenylsulfonylvinylamine

N-methyl-N-vinylbenzenesulfonamide (40 g.) was placed in a crystallizing dish 12 cm. in diameter. The dish was covered with 0.25-mil "Mylar" polyester film and set in an ice bath. The N-methyl-N-vinylbenzenesulfonamide

[M.P. 34-35° C., $\lambda_{\text{max.}}^{\text{EtOH}} = 242 \text{ m}\mu (\epsilon = 6100)$]

was prepared by condensing N-methylbenzenesulfonamide with acetylene as described by Cairns and Sauer, loc. cit. The N-methyl-N-vinylbenzenesulfonamide was exposed to a beam of 2-mev. electrons from a Van de Graaff accelerator for 66 seconds in sixty 1.1-second exposures. The electronic energy incident on the surface of the sulfonamide was 660 watt-sec./cm.².

The irradiated material, a mixture of solid and gum, was dissolved in 40 ml. of boiling ethyl acetate. Cooling the ethyl acetate solution to 0° C. caused the precipitation of 15.8 g. of N-methyl-2-phenylsulfonylvinylamine. After recrystallization from ethyl acetate the N-methyl-2-phenylsulfonylvinylamine melted at 129-130° C.,

$\lambda_{\text{max.}}^{\text{EtOH}} = 263 \text{ m}\mu (\epsilon = 15,100)$

Its infrared absorption spectrum contained a strong band at 2.95 μ indicative of an N-H bond.

Analysis.—Calcd. for C₉H₁₁NO₂S: C, 54.8; H, 5.6; mol. wt., 197. Found: C, 54.7; H, 5.5; mol. wt., in boiling acetone, 211.

The 2-sulfonylvinylamine dissolved in cold 2 N hydrochloric acid with formation of methylamine and phenylsulfonylacetalddehyde. The phenylsulfonylacetalddehyde reacted with 2,4-dinitrophenylhydrazine to give phenylsulfonylacetalddehyde 2,4-dinitrophenylhydrazone. The melting point (172-175° C.) ultraviolet spectrum and infrared spectrum of the phenylsulfonylacetalddehyde 2,4-dinitrophenylhydrazone were identical with those of an authentic sample made by condensing sodium phenyl mercaptide with the ethyl acetal of chloroacetaldehyde, oxidizing the resultant product with hydrogen peroxide in acetic acid to the ethyl acetal of phenylsulfonylacetalddehyde, and treating the latter with 2,4-dinitrophenylhydrazine dissolved in 2 N hydrochloric acid.

Analysis.—Calcd. for C₁₄H₁₂N₄O₆S: C, 46.1; H, 3.3; S, 8.8; N, 15.3. Found: C, 45.9; H, 3.4; S, 8.6; N, 15.3.

EXAMPLE 2

N-methyl-2-phenylsulfonylvinylamine

Crystalline N-methyl-N-vinylbenzenesulfonamide (100 parts) at 25° C. was exposed to an X-ray beam for 225 minutes. Dosimetry measurements with aqueous ferrous sulfate by the method of Weiss, Nucleonics 10, No. 7, 28 (1952), showed that energy from the X-ray beam was absorbed in the sample at a rate of 7200 rads per minute. Infrared analysis showed that the irradiated sulfonamide contained 25 parts (25% yield) of N-methyl-2-phenylsulfonylvinylamine.

A series of experiments was run under the same conditions except that the temperature, exposure time and state

of the sample (solid, liquid or super-cooled liquid) were varied. The results are shown in the table.

TABLE—REARRANGEMENT OF N-METHYL-N-VINYLBENZENESULFONAMIDE TO N-METHYL-2-PHENYLSULFONYLVINYLAMINE BY X-RAYS

Temp., ° C.	Exposure Time, Min.	State	Yield, Percent

EXAMPLE 3

N-methyl-2-p-tolylsulfonylvinylamine

N-methyl-N-vinyl-p-toluenesulfonamide (6.66 g.) was placed in a crystallizing dish 5.5 cm. in diameter and exposed to 440 watt-sec./cm.² of 2-mev. electrons at 25° C. as in Example 1. N-methyl-N-vinyl-p-toluenesulfonamide

[M.P. 56-56.5° C., $\lambda_{\text{max.}}^{\text{EtOH}} = 240 \text{ m}\mu (\epsilon = 8500)$]

was prepared from N-methyl-p-toluenesulfonamide and acetylene by the method of Cairns and Sauer, loc. cit. Crystallization of the reaction mixture from ethyl acetate gave 4.77 g. of N-methyl-2-p-tolylsulfonylvinylamine

[M.P. = 122-123° C., $\lambda_{\text{max.}}^{\text{EtOH}} = 264 \text{ m}\mu (\epsilon = 16,200)$]

The infrared absorption spectrum had a strong N-H band at 2.95 μ .

Analysis.—Calcd. for C₁₀H₁₃N₂OS: C, 56.9; H, 6.2; N, 6.6; S, 15.2. Found: C, 57.0; H, 6.2; N, 6.7; S, 15.3.

Treatment of N-methyl-2-p-tolylsulfonylvinylamine with a hot solution of 2,4-dinitrophenylhydrazine in aqueous ethanol containing hydrochloric acid gave p-tolylsulfonylacetalddehyde 2,4-dinitrophenylhydrazone, M.P. 184-186° C.

Analysis.—Calcd. for C₁₅H₁₄N₄O₆S: C, 47.6; H, 3.7; N, 14.8; S, 8.5. Found: C, 47.8; H, 3.7; N, 14.3; S, 8.3.

EXAMPLE 4

N-methyl-2-p-tolylsulfonylvinylamine

N-methyl-N-vinyl-p-toluenesulfonamide (100 parts) was exposed to an X-ray beam at 25° C. for 77 minutes. Ferrous sulfate dosimetry showed that X-ray energy was absorbed in the sample at a rate of 6800 rads/min. The irradiated sulfonamide contained 13 parts of N-methyl-2-p-tolylsulfonylvinylamine. In experiments that were identical except for the temperature, 5 parts of the vinylamine was formed at 81° C. and 6 parts was formed at -76° C.

EXAMPLE 5

N-n-butyl-2-p-tolylsulfonylvinylamine

N-n-butyl-N-vinyl-p-toluenesulfonamide

[B.P. = 126°/0.1 mm.; $n_D^{25} = 1.5279$;

$\lambda_{\text{max.}}^{\text{EtOH}} = 242 \text{ m}\mu (\epsilon = 7340)$]

was prepared from N-butyl-p-toluenesulfonamide and acetylene by the method of Cairns and Sauer, loc. cit. N-n-butyl-N-vinyl-p-toluenesulfonamide (1.0 g.) was placed in a crystallizing dish 2.0 cm. in diameter and exposed to 660 watt-sec./cm.² of 2-mev. electrons, at 25°, as in Example 1. The infrared absorption spectrum of

5
2-methylvinylamine was added to the mixture. At the reaction mixture had a strong N—H band at 2.95μ , and bands of absorption due to the presence of hydroxyl groups. $\lambda_{\text{max}}^{\text{EtOH}} = 267 \text{ m}\mu (k=45)$

Treatment of 198 parts of product with a hot solution of 2,4-dinitrophenylhydrazine in aqueous ethanol containing hydrochloric acid gave 200 parts of p-tolylsulfonylacetalddehyde-2,4-dinitrophenylhydrazone, M.P. = 184–186° C. The yield of the rearrangement product, N-n-butyl-2-p-tolylsulfonylamine, calculated from the yield of p-tolylsulfonylacetalddehyde-2,4-dinitrophenylhydrazone isolated, was more than 70%.

EXAMPLE 6

N-methyl-2-n-butylsulfonylvinylamine

N-methyl-N-vinylbutanesulfonamide (B.P. = 100° C./2 mm.; $n_{\text{D}}^{25} = 1.4691$) was prepared from N-methylbutanesulfonamide and acetylene according to the method of Cairns and Sauer, loc. cit. N-methyl-N-vinylbutanesulfonamide (1.0 g.) was placed in a crystallizing dish 2.0 cm. in diameter and exposed to 2200 watt-sec./cm.² of 2-mev. electrons, at 25° C. The infrared absorption spectrum of the irradiated sulfonamide showed a strong N—H band at 2.95μ , and the ultraviolet spectrum had

$$\lambda_{\text{max}}^{\text{EtOH}} = 243 \text{ m}\mu (k=6.7)$$

indicating that rearrangement to N-methyl-2-n-butylsulfonylvinylamine had occurred.

Alkaline hydrolysis and quantitative determination of the liberated methylamine showed that the reaction mixture contained 13.4% by weight of N-methyl-2-n-butylsulfonylvinylamine.

EXAMPLE 7

N-methyl-2-methylsulfonylvinylamine

N-methyl-N-vinylmethanesulfonamide (1.0 g.) was placed in a crystallizing dish 2.0 cm. in diameter and exposed to 1980 watt-sec./cm.² of 2-mev. electrons. Analysis of the irradiated sulfonamide showed that it contained 9.3% by weight of N-methyl-2-methylsulfonylvinylamine.

EXAMPLE 8

N-methyl-2-β-naphthylsulfonylvinylamine

N-methyl-N-vinyl-β-naphthalenesulfonamide was prepared by treating the p-toluenesulfonic acid ester of N-methyl-N-(2-hydroxyethyl)-β-naphthalenesulfonamide with alcoholic potassium hydroxide. Ten grams of the ester was refluxed for 2 hours with a solution of 5 grams potassium hydroxide in 50 ml. of 95% ethanol. The reaction mixture was diluted with 50 ml. water and extracted with ether. The ether was removed by vacuum evaporation and the N-methyl-N-vinyl-β-naphthalenesulfonamide distilled through a short path distillation apparatus. The fraction (3.3 grams) boiling at 150–160° C./0.05 mm. as collected.

Analysis.—Calcd. for $\text{C}_{13}\text{H}_{13}\text{SO}_2\text{N}$: C, 63.2; H, 5.26; N, 5.67. Found: C, 63.36; H, 5.37; N, 5.85.

The structure of the product was further confirmed by its infrared spectrum.

N-methyl-N-vinyl-β-naphthalenesulfonamide (0.47 gram) was placed in an open crystallizing dish 2.0 cm.² in diameter and exposed to 660 watt-sec./cm.² of 2-mev. electrons at 25° C. The viscous product was taken up in hot methanol. Cooling the methanol solution caused the precipitation of 0.04 gram of N-methyl-2-β-naphthylsulfonylvinylamine (M.P. = 134–136° C.).

Analysis.—Calcd. for $\text{C}_{13}\text{H}_{13}\text{SO}_2\text{N}$: N, 5.67. Found: N, 5.77.

EXAMPLE 9

N-methyl-2-phenylsulfonylvinylamine

A solution of 250 parts of N-methyl-N-vinyl-benzenesulfonamide and 1000 parts by volume of methanol was placed in an ice bath and exposed to a beam of 2-mev.

5
6
In benzene oil culture, 30 parts of N-methyl-2-phenylsulfonylvinylamine was exposed to 2-mev. electrons for 165 seconds under the conditions of Example 1. Ultraviolet analysis of the solution showed that 30 parts of N-methyl-2-phenylsulfonylvinylamine had been formed.

EXAMPLE 10

N-methyl-β-p-tolylsulfonyl-α-styrylamine

N-methyl-N-α-styryl-p-toluenesulfonamide (0.5 g.) was placed in a small open crystallizing dish of cross section 3.14 cm.², and exposed to 550 watt-sec./cm.² of 2-mev. electrons at 40–60° C. A portion of the viscous product was dissolved in hot ethyl acetate. On cooling, white crystalline N-methyl-β-p-tolylsulfonyl-α-styrylamine precipitated, M.P. 105–106° C.

Analysis.—Calcd. for $\text{C}_{16}\text{H}_{17}\text{SO}_2\text{N}$: C, 66.88; H, 5.96. Found: C, 67.03; H, 6.33.

The structure of the product was further established by its infrared spectrum and its ultraviolet spectrum

$$[\lambda_{\text{max}}^{\text{EtOH}} = 275 (\epsilon = 13,700)]$$

The yield of N-methyl-β-p-tolylsulfonyl-α-styrylamine was found to be 80% by hydrolysis of a portion of the crude reaction product with 5% sodium hydroxide and titration of liberated methylamine.

The N-methyl-N-α-styryl-p-toluenesulfonamide was prepared as follows: A solution of 57 grams of p-toluenesulfonyl chloride in 150 ml. of pyridine was added slowly to a solution of 15 grams of α-N-methyl-aminophenylethanol in 125 ml. of pyridine, while the temperature was maintained at 40–45° C. The mixture was poured into a mixture of ice and hydrochloric acid and extracted with benzene. The crystalline N-methyl-N-p-tolylsulfonyl-2-amino-2-phenethyl-p-toluenesulfonate (22 grams, M.P. 103–104° C.) obtained on evaporating the dried benzene extract was refluxed for 2.5 hours with a solution of 6 grams of potassium hydroxide in 75 ml. of 95% alcohol. The cooled reaction mixture was slurried with 125 ml. of water and filtered to give 10.2 grams of crystalline N-methyl-N-α-styryl-p-toluenesulfonamide (M.P. 82–83° C.).

Analysis.—Calcd. for $\text{C}_{16}\text{H}_{17}\text{SO}_2\text{N}$: C, 66.88; H, 5.96. Found: C, 66.95; H, 6.25.

The structure of the compound was further confirmed by its ultraviolet spectrum

$$[\lambda_{\text{max}}^{\text{EtOH}} = 235 (\epsilon = 18,300)]$$

and its infrared spectrum.

The new aminovinylsulfones of this invention are useful as inhibitors for vinyl polymerization, and are especially effective in inhibiting the polymerization of vinyl acetate. They are also useful for crosslinking polyvinyl alcohol and other hydroxylated polymers; one merely heats a mixture of the polymer and sulfone with water and a little mineral acid to obtain crosslinked polymer, probably by acetal formation between the polymer and the sulfonylacetaldehyde formed in situ.

Since obvious modifications in the invention will occur to those skilled in the chemical arts, we propose to be bound solely by the appended claims.

The embodiments of the invention in which an exclusive property or privilege is claimed are defined as follows:

1. The method of synthesizing a compound of the formula

65
60
55
50
45
wherein R and R' are hydrocarbon radicals in which any unsaturation is aromatic and which possess not more than 12 carbon atoms each, which comprises subjecting to about 0.1 to 10,000 watt-sec./cm.² of surface thereof of high energy, ionizing radiation having an energy of at least about 0.1 mev. a precursor of the formula

70
75
R and R' being as defined above, thereby rearranging said

precursor, and subsequently recovering the compound of the formula

from irradiated material.

2. The method of claim 1 wherein the precursor is a solid;

3. The method of claim 1 wherein the high energy, ionizing radiation is particle radiation.

4. The method of claim 1 wherein the high energy, ionizing radiation is electrons.

5. The method of claim 1 wherein the high energy, ionizing radiation is electromagnetic radiation.

6. The method of claim 1 wherein the high energy, ionizing radiation is X-rays.

7. The method of synthesizing the amine N-methyl-2-phenylsulfonylvinylamine which comprises subjecting N-methyl-N-vinylbenzenesulfonamide to about 0.1 to 10,000 watt-sec./cm.² of surface thereof of high energy, ionizing radiation having an energy of at least about 0.1 mev. and subsequently recovering said amine from the irradiated material.

8. The method of synthesizing the amine N-methyl-2-p-tolylsulfonylvinylamine which comprises subjecting N-methyl-N-vinyl-p-toluenesulfonamide to about 0.1 to 10,000 watt-sec./cm.² of surface thereof of high energy, ionizing radiation having an energy of at least about 0.1 mev. and subsequently recovering said amine from the irradiated material.

9. The method of synthesizing the amine N-n-butyl-2-p-tolylsulfonylvinylamine which comprises subjecting N-n-butyl-N-vinyl-p-toluenesulfonamide to about 0.1 to 10,000 watt-sec./cm.² of surface thereof of high energy, ionizing radiation having an energy of at least about 0.1 mev. and subsequently recovering said amine from the irradiated material.

10. The method of synthesizing the amine N-methyl-2- β -naphthylsulfonylvinylamine which comprises subjecting N-methyl-N-vinyl- β -naphthalenesulfonamide to about 0.1 to 10,000 watt-sec./cm.² of surface thereof of high energy, ionizing radiation having an energy of at least about 0.1 mev. and subsequently recovering said amine from the irradiated material.

11. The method of synthesizing the amine N-methyl-2-n-butylsulfonylvinylamine which comprises subjecting N-methyl-N-vinylbutanesulfonamide to about 0.1 to 10,000 watt-sec./cm.² of surface thereof of high energy, ionizing radiation having an energy of at least about 0.1 mev. and subsequently recovering said amine from the irradiated material.

12. The method of synthesizing the amine N-methyl-2-methylsulfonylvinylamine which comprises subjecting N-methyl-N-vinylmethanesulfonamide to about 0.1 to 10,000 watt-sec./cm.² of surface thereof of high energy, ionizing radiation having an energy of at least about 0.1 mev. and subsequently recovering said amine from the irradiated material.

13. The method of synthesizing the amine N-methyl- β -p-tolylsulfonyl- α -styrylamine which comprises subjecting N-methyl-N- α -styryl-p-toluenesulfonamide to about 0.1 to 10,000 watt-sec./cm.² of surface thereof of high energy, ionizing radiation having an energy of at least about 0.1 mev. and subsequently recovering said amine from the irradiated material.
